UNITED STATES PATENT OFFICE.

JAMES C. LEDBETTER, OF BROOKLYN, NEW YORK, ASSIGNEE, BY MESNE ASSIGNMENTS, TO THE PROSPERITY COMPANY, INC., A CORPORATION OF NEW YORK.

CONVEYER PLAIT PRESS.

Application filed September 5, 1924. Serial No. 736,003.

This invention relates to garment pressing machinery and particularly to plait holders and the like for aiding the permanent pressing and forming of plaits in goods; and the invention especially relates to conveyer press plait holders designed to turn out plaited work at a rapid rate.

Among other things, an object of this invention is to produce improvements in plait holders over and above the construction shown in the ironing board plait holder Dwoirin Patent 1,501,044 granted July 15, 1924.

A further and main object of the invention is to produce a plait holder conveyer pressing machine whereby one or more work holding trays may be operated on one or more tracks whereby the plait holder is conveyed into the jaws of a pressing machine for permanently baking in and curing plaits in goods.

A further object is to produce an improved plait holder constructed as an attachment which may be mounted on ironing boards or ordinary hand ironing work.

Having this and other objects in view the invention relates to a certain combination and relation of parts, an example of which is shown in the accompanying drawings, and the principle of which is set forth in the following specification and claims.

Figure 1 shows a diagrammatic front view of pressing machine jaws in open position with a track disposed alongside thereof and with a plait holder and plaited work carrying car or tray movably carried on the track; and the tray is shown in position ready to have the work supported therein pressed between the jaws and the press head is in the act of descending.

Figure 2 shows a plan view of the plait holder work carrying tray or car with the head of the press removed so as to disclose a general plan view of the plurality of plait forming and pressing fingers.

Figure 3 shows a plan view of a plait holder attachment constructed in accordance with the plans of this invention, and as applied to an ordinary ironing board.

Figure 4 is a sectional view showing one of the plait holder pressure fingers as developed along the line 4-4 of Figure 7.

Figure 5 is a view taken on the line 5-5 of Figure 7 and shows a front elevation of a ratchet wheel designed to hold the plait

ing pressure fingers down in operative position, and shows a shaft common to a large number of plait fingers.

Figure 6 shows a sectional view as developed on the line 6-6 and illustrates in side elevation the plait pressure finger and cooperating ratchet by which the finger is ratcheted down and held against the work.

Figure 7 is a plan fragmentary view of one end of the tray frame with a section thereof broken away in order to show the plait holding fingers in full size on the tray frame.

Figure 8 shows a sectional view taken on the line 8-8 of Figure 7 and illustrates a spring pressed locking handle designed to simultaneously release all the plait holding fingers as well as permitting the plait holding fingers to be individually and separately pressed down against the work to hold each successive plait as it is manually formed and shaped up in the goods by the operator performing the work.

Figure 9 illustrates an end elevation of a hand wheel used to simultaneously open all the plait holding fingers whereby the work is removed from the tray or ironing board.

A description will first be given of the combination plait and work carrying tray employed as a conveyer for use in connection with an ordinary pressing machine.

A pressing machine is shown in diagrammatic form and has the usual pressing jaw members such as the head 10 and buck 11 and the jaws open and close on the work as well known to those conversant with the art. The pressing jaws 10 and 11 are suitably heated by any appropriate means and are either operated manually or by power means depending upon the type of garment machine at hand. A conveyer track comprising parallel rails 12 is disposed alongside the pressing jaws and the track may be so constructed that a double roll in and roll out tray conveyer may be used in conjunction with a pressing machine, but for the purpose of disclosing the present invention, I illustrate one track only. A car or tray comprising a rectangular frame 13 is provided with car wheels or rollers 14 journaled on the frame and this car travels on the track in and out of the press.

The rails 12 are preferably depressed at 15 for the purpose of bringing the car or tray 13 to rest at a predetermined point in exact 110

alignment with the pressing jaws. Furthermore the depressed, indented, or low track portions 15 permit the tray 13 to gravitate downwardly against the lower press jaw 11 just at the moment the tray comes to rest. This final downward motion of the tray when it enters the low track part 15 permits the tray center cloth webbing 16 to make contact with the pressing face 17 of the lower press jaw 11 which permits the press head 10 to move down against the tray web 16 without distorting it since the said tray webbing 16 rests in positive contact with the lower jaw. As the car 13 moves out of the press, the hill or rise in the track at the depression 15 immediately lifts the frame 13 above the edge of the press in order that the rectangular metal frame 13 not strike the edges or corners of the lower jaw 11 as the tray begins to leave the press.

The foregoing description covers in general any suitable combination of pressing machine and tray upon which my improved plait holder is installed and combined therewith; and my invention not only consists in a new combination of a conveyer plait holding press, but relates to improvements in the construction of certain nimble and flexible plait holding spring pressed fingers whereby each finger may be pressed individually down upon the work, but thereafter all the fingers rise at one time saving much of the operator's time in removing the work as well as decreasing the cost of construction as compared to plait holders suggested in the past.

In Figure 7 there is shown a fragmentary plan corner or end view of my improved plait holder mounted on the tray frame, and the tray frame shown in Figure 7 is stripped of its webbing for clarity, and the frame has a line of holes 20 by which central webbing 16 is laced, as indicated at 21, into the frame 13. The plait holding attachment is incorporated in the frame as by mounting it on the frame itself or by setting a wide plate or board 22 into the frame as a part of the frame structure. A plait holder shaft 23 has each end thereof journaled in the frame and the shaft carries a plurality of ratchet wheels 24 fixed thereon in spaced relation and each spaced toothed wheel or ratchet wheel performs the function of holding a plait pressing finger down in operative position.

A flexible plate spring plait holding finger 28 has one end thereof split and this bifurcated end is curled to form a bearing encircling the hub 30 of the ratchet 24, the arrangement being such that the said ratchet wheel 24 is disposed between the forked ends 29 of the pressing fingers 28. The ratchet wheel 24 and the plait holding finger 28 are rotatably held together inasmuch as the curled end 29 is passed around the ratchet wheel hub 30; and the said ratchet wheel is

anchored or fixed to the shaft 23 while the part 28 may pivot relatively to and turn on the ratchet wheel hub 30. Each pressure finger assembly 28 and ratchet wheel 24 is constructed identically one like the other and 70 and understanding of one is sufficient for all. Each plait holding finger 28 is provided with an integral spring catch pawl 31 which is cut from the center of the plate steel member 28 thus forming the forked ends 29. This 75 spring pressed pawl rests in engagement with the ratchet wheel 24 and snaps over each successive tooth as the finger 28 is driven or pressed down manually by the operator on the work to hold individual plaits in 80 position.

A press button or handle 34 may, if desired, be anchored to the spring plate finger 28, though the button 34 may be omitted therefrom and the operator may as well 85 press directly on the spring 28 to bring it down into holding and pressing position on the plaited work. The outer flat end 35 of the plait holding finger provides a large bearing surface by which the plaits in the 90 work are held under the pressure of the flat finger part 35 which may spread across several plaits. Bearings 36 may be carried on the shaft 23 and anchored to the plate 22 at intervals along the shaft in order that the 95 shaft 23 be positively held in alignment when considerable pressure is being exerted on the work by the several plait holding spring fingers 28 for by the time the large number of spring fingers are bearing down 100 on the work a considerable pressure is exerted on the shaft 23 though comparatively little pressure is exerted by any one lone finger.

A hand wheel 39 is anchored to one end 105 of the shaft 23 and the operator may rotate this hand wheel a partial revolution, say 90 degrees to swing the entire line of plait holding fingers on the shaft up in vertical position as shown in Figure 8, and all the 110 plait holders are instantly and simultaneously lifted off of the work whereas in old patented plait holders suggested in the past, only one finger was lifted at a time. Locking means is employed to hold the plurality 115 of spring pressed fingers down in operative position and this locking means is shown in sectional detail in Figure 8 wherein the locking wheel 40 is anchored to the shaft 23. This toothed locking wheel is made 120 with lock notches 41 engaged by a dog 42. The dog is pivotally carried on a bearing pin 43 anchored to the frame 13. A spring 44 has one end thereof anchored to the frame 13 while the free end yieldingly presses 125 against the dog 42.

Pressure of the spring 44 is overcome by a pull exerted on a handle 46 which is anchored to the dog 42. The operator, by grasping the handle 46 in one hand and the 130

wheel 39 in the other hand, first overcomes the pressure of the spring 44 and then the wheel 39 is rotated clockwise to swing all the plait fingers 28 up into vertical position as shown in Figure 8 thereby instantly releasing all fingers from the work which frees the plaited work or goods in the tray and enables the operator to quickly remove the same from the press and from the tray.

- 10 This machine may be used for large production work in plaiting goods since the material to be plaited may be rolled off the bolt and the plaits formed up by the operator, and feed through the pressing machine.
- 15 Each finger 28-35 is large enough to bear down on two or three folds or plaits and will even cover more where the plaits are in narrower folds.

The conveyer tray 13 is shown equipped 20 with a plaiting finger unit at each end for the purpose of securely holding each edge of the goods; and the construction and operation of the two units is identical.

Referring to Figure 3, a description will 25 now be given of an improved ironing board for domestic use and with which my improved plait holding attachment may be used. This attachment for ironing boards may comprise a frame plate 48 carrying a shaft 49 on one end of which is anchored a wheel 50. A locking dog and handle 51 works against the shaft 49 to hold it in fixed position. The plurality of spring 30 pressed fingers 52, as already described, is 35 carried on the shaft and is adapted to resiliently press down on the work such as a

skirt S held on the ironing board B. The construction and operation of the ironing board plait holder is identical with the tray or car hereinbefore described. The ironing 40 board plait holder 48 is manufactured in attachment form and is provided with a suitable clamp, if necessary, by which it is fastened to the ironing board B.

What I claim is:

1. Plait holding means comprising a frame embodying a work support, a shaft rotatably mounted therein, a plurality of spring pressed fold retaining fingers journaled on the shaft, a ratchet wheel fixed to 50 the shaft, a pawl attached to each finger and locking against the ratchet wheel to hold the finger down on the plait fold, and unlocking means cooperating with the shaft by which all the fingers are simultaneously 55 lifted off the work.

2. Plait holding means comprising, a frame embodying a work support, a shaft rotatably mounted therein, a plurality of spring pressed fold retaining fingers journaled on the shaft, locking means holding each individual finger down on the work, a hand operable member by which the shaft is turned a partial revolution to lift the fingers 60 off the work, locking means to fix the hand operable member against operation, and unlocking means by which the hand operable member is released.

In testimony whereof I affix my signature.

JAMES C. LEDBETTER.
